GAS AND AIR OPERATED VALVE

William J. McGoldrick, Minneapolis, Minn., assignor to Minneapolis-Honeywell Regulator Company, Minneapolis, Minn., a corporation of Delaware

Application February 12, 1940, Serial No. 318,419

10 Claims. (Cl. 158—99)

The present invention relates to the operation and control of valves, particularly in gas fired combustion systems employing forced draft. In such systems diaphragm type gas control valves are commonly used and my invention deals primarily with a novel and improved arrangement for operating such a valve in the type of system referred to.

In the control of forced draft combustion systems employing gaseous fuel it is important that positive means be provided for actuating the fuel valve at the proper times and in the proper manner.

It is the object of my invention to provide an arrangement offering assurance of the attainment of the above ends in the simplest, most economical and effective manner, the arrangement comprising means which act directly to perform their respective cooperative functions.

More specifically an object of my invention is to provide combined air pressure and gas pressure actuated valve means in a forced draft combustion system so arranged that the valve means are positively actuated in the desired direction directly in response to the application of air or gas thereto.

Another object of my invention is to provide an air operated diaphragm valve in combination with means providing for quick and positive closing of the valve.

Another object of my invention is to provide an air operated diaphragm valve in combination with means for applying gas pressure to one side of the diaphragm to assist in operation of the valve.

The single figure of the drawing represents a gas fired forced draft combustion system embodying my invention therein.

Referring to the drawing, numeral 10 designates a gas fired furnace of usual type there being located within the furnace a gas burner 11 through which gas is supplied through a conduit 12. Interposed in the conduit 12 is a diaphragm type gas valve indicated generally at 13. Conduit 12 ahead of the valve 13 may communicate with any suitable source of fluid fuel such as gas. Located adjacent the burner 11 is a small pilot burner 14, the purpose of which is to ignite the flame of the main burner 11 and gas is continuously supplied to the pilot burner 14 by means of a tube 15 communicating with the conduit 12 ahead of the valve 13. Numeral 16 designates generally a safety pilot comprising a bimetal element 17 located so as to be normally heated by

the flame of the pilot burner and flexed into engagement with a fixed electrical contact 18.

The furnace 10 is of a forced draft type, numeral 21 designating a forced draft fan driven by an electrical motor and having a discharge duct 22 communicating with the lower part of the furnace.

The body portion of the valve 13 has an inlet at 23 and an outlet at 24, there being a passageway through the valve controlled by a valve member 25 to which is connected a valve stem 26. The upper part of the valve 13 comprises a conically shaped portion 27 having a flange 28. Numeral 29 designates a dish shaped member having an opening 30 in its lower portion, this member constituting the lower part of a diaphragm chamber of the valve. The peripheral portions of a seal-off diaphragm 31 are engaged between the flange 28 of portion 27 and the lower surface of the dish shaped member 29, these parts being secured together in any suitable manner. The valve stem 26 extends through the seal-off diaphragm 31, and the portions of the seal-off diaphragm adjacent the valve stem are secured between a pair of collars 32 and 33 secured to the valve stem in any suitable manner. Numeral 34 designates a ring shaped member of a size externally as great as the greater dimension of the flange of the member 29. The ring 34 is superimposed on the flange of the member 29 with the peripheral portions of the diaphragm 35 secured between the ring 34 and the flange of the member 29. Numeral 36 designates a flanged cover element for the diaphragm chamber having a flange of the same size as the ring 34, the flange being in engagement therewith, the flanges, the ring 34 and the peripheral portions of the diaphragm 35 all being secured together in any suitable manner. The valve stem 26 passes through the diaphragm 35 and the portions of the diaphragm adjacent the valve stem are secured between two discs 37 and 38 which are attached to the valve stem in any suitable manner.

Numeral 40 designates a three-way pilot valve 45 of known type operated by an electric solenoid within the housing 41. The three-way pilot valve comprises a body portion 42 having an opening 43 therewithin. A channel 44 in the body portion 42 communicates with the side of the opening 43 and a channel 45 in the body portion 42 communicates with the lower part of the opening 43 and form a seat for the valve member 46. The upper part of the opening 43 is closed by a plug 47 in screw threaded engagement with the body portion 42 and having a central opening

through which extends the stem 48 of the valve member 46. The space 43 is in open communication with an open space above the plug 47 through the opening in the plug around the valve stem and the latter space communicates with the conduit 12 ahead of the valve 13 by means of the tube 49. The valve member 46 is so shaped as to be able to close off communication through the channel 45 and the opening through the plug 47 also forms a valve seat so that the valve member 46 can be moved upwardly to close off communication through the plug 47. When the solenoid within the housing 41 is deenergized the pilot valve is in the position shown. In this position gas passes through the tube 49, through the plug 47 and channel 44 into the space above diaphragm 35, the pressure thus maintaining the valve 13 closed. When the solenoid within the housing 41 is energized the valve member 46 is moved upwardly so as to cut off communication of gas pressure through the plug 41, and to release the gas from above the diaphragm 35 so that it can pass through the channels 44 and 45. The channel 45 communicates with an auxiliary pilot burner 50 by means of a tube 51.

Numerical 52 designates a thermostat which may be of a well known type comprising a bimetal element 53 having a movable switch blade 54 attached thereto, the switch blade 54 cooperating with a fixed electrical contact 55. Upon a drop in temperature to which the thermostat 52 is responsive, to a predetermined value the blade 54 engages with the contact 55.

In operation, whenever the thermostat 52 makes contact as described, a circuit is completed for the draft fan as follows: from wire 60 through the safety pilot 16, wire 61, thermostatic element 53, blade 54, contact 55, wire 62, wire 63, the fan motor, wire 64 and wire 65, the wires 60 and 65 being connected to any suitable line conductors. At the same time a circuit is completed for the solenoid within housing 41 as follows: from wire 60 to safety pilot 16, wire 61, thermostatic element 53, blade 54, contact 55, wire 62, wire 66, the solenoid within housing 41 back to wire 65. As soon as these circuits are completed the draft fan starts in operation and the valve member 46 is moved to its upper position to release the gas from diaphragm 35 as above described. As soon as an appreciable amount of pressure has been built up in discharge duct 22 this air pressure is communicated to the chamber on the lower side of diaphragm 35 through tube 39 and the diaphragm 35 is lifted in a manner to open the valve 13. As soon as the valve is open gas is supplied to the burner 11 and heating commences, and continues as long as the thermostat 52 is calling for heat. When the thermostat becomes satisfied the above traced circuits are interrupted, the fan stops and the pilot valve 40 assumes the position shown on the drawing. Inasmuch as the fan and its driving motor have a certain amount of momentum the fan does not stop as soon as its motor is deenergized and therefore the pressure in discharge duct 22 does not immediately disappear. Therefore, without other means cooperating to close the valve 13 it would be delayed in its closing action until the pressure had dropped sufficiently within the duct 22 and the chamber below the diaphragm 35. To avoid this condition and in order to bring about quick and positive closing of the valve the three-way pilot valve 40 is provided to permit gas pressure to be

applied to the upper side of the diaphragm 35 as soon as the fan motor is deenergized in order to force the diaphragm downward. Thus whenever the fan motor is deenergized the three-way valve assumes the position shown on the drawing and gas pressure passes through the tubes 49, the opening in plug 47, space 43 and channel 44 into the chamber about diaphragm 39. The pressure acting on the upper side of diaphragm 35 quickly closes the valve preventing any delayed action which would otherwise take place.

From the foregoing those skilled in the art will appreciate that I have provided an efficient and positive acting arrangement whereby a diaphragm valve may be operated by means of a draft pressure from a draft fan, and wherein the valve will be operated with the desired quick movements by reason of the arrangement for causing gas pressure to act on the upper side of the diaphragm for closing.

The single embodiment of my invention which I have disclosed is representative and the scope of the invention is to be determined not in accordance with my disclosure but only by the scope of the appended claims.

I claim as my invention:

1. In a heating system, in combination, combustion means comprising a furnace having forced draft means, fuel supply means including a diaphragm type valve having a diaphragm in a diaphragm chamber, means for exposing one side of said diaphragm to draft air pressure for opening the valve and means for exposing the other side of the diaphragm to fuel at substantially supply pressure, said fuel pressure supplying the power for closing the valve and maintaining it in closed position, said last means including means for releasing fuel pressure from said other side of the diaphragm to permit the valve to be opened by the draft air pressure.

2. In a gas fired heating system, in combination, a furnace, forced draft means and gas supply control means including a gas valve having a diaphragm located within a diaphragm chamber, means for conveying air pressure from said forced draft means to said diaphragm chamber for moving said diaphragm in one direction, pilot valve means controlling the admission to and release of gas from the chamber on the opposite side of the diaphragm and control means for starting the forced draft means in operation and at substantially the same time operating said pilot valve means to cause gas to be released from said diaphragm chamber.

3. In a gas fired combustion system, in combination, control means comprising a valve having a diaphragm chamber with a diaphragm dividing the chamber into two parts, forced draft means, means for conveying draft air to the space on one side of the diaphragm for opening the valve, means comprising a pilot valve for admitting gas pressure to and releasing gas from the space on the other side of the diaphragm, and thermostatic means controlling the forced draft means and said pilot valve means to substantially simultaneously energize said forced draft means and actuate said pilot valve means to release gas from the space on the other side of said diaphragm.

4. In a gas fired heating system, in combination, a furnace, forced draft means and gas supply control means including a gas valve having a diaphragm located within a diaphragm chamber, means conveying gas pressure to one side of said diaphragm urging said valve in closing di-

reaction, means for cutting off the supply of gas to said one side of the diaphragm and releasing the pressure acting thereagainst, and means conveying draft air from the discharge side of said forced draft means to the other side of said diaphragm for opening said valve whereby said valve is not opened until after the establishment of draft.

5. In a gas fired heating system, in combination, a furnace, forced draft means and gas supply control means including a gas valve having a diaphragm located within a diaphragm chamber, means comprising a three-way pilot valve for admitting pressure to and releasing pressure from one side of the diaphragm, means for conveying draft air from the discharge side of said forced draft means to the other side of said diaphragm for opening said valve, and means comprising a thermostat controlling said forced draft means and three-way pilot valve to substantially simultaneously energize said forced draft means and actuate said pilot valve to release pressure from said one side of said diaphragm.

6. A fuel control device comprising in combination, a combustion chamber, a conduit for conveying fuel to said combustion chamber, a valve in said conduit for controlling the flow of fuel, a forced draft means for supplying combustion supporting air to said combustion chamber, means controlling said valve comprising a diaphragm and a pair of diaphragm chambers, means for subjecting one of said chambers to pressure for closing said valve and for relieving said pressure when it is desired to open said valve, and means connecting the other chamber with the pressure created by said forced draft means for opening said valve.

7. A fuel control device comprising in combination a combustion chamber, a conduit for conveying fuel to said combustion chamber, a valve in said conduit for controlling the flow of fuel, a forced draft means for supplying combustion supporting air to said combustion chamber, means controlling said valve comprising a diaphragm and a pair of diaphragm chambers, means for alternately subjecting one of said chambers to pressure and venting it to atmosphere, said diaphragm tending to move said valve to closed position when said one chamber is subjected to pressure, means connecting said other chamber to the downstream side of said forced draft means whereby said valve may be opened only if said forced draft means is operative, and means for substantially simultaneously venting said one chamber to atmosphere and rendering said forced draft means operative.

8. A gas burner control system comprising in combination, a gas supply conduit for delivering

gas under pressure to a burner, forced draft means for supplying combustion supporting air, a valve in said gas supply conduit controlling the flow of gas therethrough, means for actuating said valve including a diaphragm and first and second diaphragm chambers, control means for alternately connecting said first chamber to the pressure of gas from the upstream side of said valve for closing said valve and venting said chamber, means connecting said second chamber to the downstream side of said forced draft means for opening said valve, and means responsive to a demand for heat for venting said first chamber and energizing said forced draft means whereby the pressure developed by said forced draft means opens said valve.

9. A gas burner control system comprising in combination, a gas supply conduit for delivering gas under pressure to a burner, forced draft means for supplying combustion supporting air, a valve in said gas supply conduit controlling the flow of gas therethrough, means for actuating said valve including a diaphragm and first and second diaphragm chambers, a valve stem connecting said diaphragm and valve, a second diaphragm connected to said valve stem and sealing said second chamber from the gas pressure at said valve, control means for alternately connecting said first chamber to the pressure of gas from the upstream side of said valve for closing said valve and venting said chamber, means connecting said second chamber to the downstream side of said forced draft means, for opening said valve and means responsive to a demand for heat for venting said first chamber and energizing said forced draft means whereby the pressure developed by said forced draft means opens said valve.

10. In a gas fired heating system in combination, a gas valve for controlling the supply of gas to a burner, a diaphragm located within a diaphragm chamber for moving said valve between open and closed positions, pilot valve means for controlling the admission of gas to one side of said diaphragm for closing said gas valve when there is no demand for burner operation and for bleeding said gas pressure in response to a demand for burner operation, means preventing the pressure of said gas from opening said gas valve, and means for admitting air under pressure from a forced draft means to said other side of said diaphragm for causing opening of said gas valve when said pilot valve means is in a position to bleed gas from said one side of said diaphragm and said forced draft means is in operation.

WILLIAM J. McGOLDRICK.
